ATTORNEY

UNITED STATES PATENT OFFICE.

FRANK C. HINCKLEY, OF STRATFORD, CONNECTICUT, ASSIGNOR TO COLUMBIA PHONOGRAPH COMPANY, INC., OF BRIDGEPORT, CONNECTICUT, A CORPORATION OF NEW YORK.

SOUND BOX.

Application filed June 12, 1926. Serial No. 115,506.

This invention relates to talking machines and the like, and has particular reference to the reproducer and method of mounting the same.

5 An object of the present invention is to provide a mounting for the sound-box, or reproducer, which mounting entirely insulates the sound-box from the tone-arm.

10 Another object of the invention is to provide a talking machine or the like, in which the sound-box is flexibly or yieldably attached to a connector or nipple adapted to be secured to, or in, the tone-arm.

15 An additional object is to generally improve and simplify the construction of the sound-box proper.

20 While in the accompanying drawing, and following description, I have shown a satisfactory embodiment of the invention, it is to be understood that this is by way of illustration only, and that reference must be had to the appended claims for an exact definition of the limitations of the invention.

In the drawing—

25 Fig. 1 is a front elevational view of a sound-box made in accordance with my invention;

Fig. 2 is a rear elevational view thereof; and

30 Fig. 3 is a sectional view.

Referring in detail to the drawing,—the sound-box comprises a ring 5 having an inwardly extending annular flange 6 at its forward side. The ring proper at its rear edge is in contact with a disc-shaped back 7, which at its outer edge is reduced in thickness to provide a shoulder 8. Ring 5 is of a thickness equalling the width of the reduced portion of the back, and when these parts are clamped together, the ring fills this space completely and abuts against the annular shoulder 8. Screws or other suitable fastening means 9 are used to secure the back to the ring. When the ring and back are secured together, there is the correct space between the back and the flange 6 for any suitable gaskets 10 which support a diaphragm 11. This diaphragm may be of any suitable construction, but is, preferably, shaped substantially like that shown, and is of very thin metal.

Disposed over the forward face of the sound-box is a guard or cover 12, having an open design cut therein so as to permit free movement of the atmosphere during the reproducing operation when the diaphragm is being vibrated by means of a needle arm 13, which is pivotally mounted between screws or other means 14 carried by lugs 15, formed with, or secured to the sound-box. This 55 needle arm is, as usual, provided with a thumb screw 16 for binding a stylus point or needle 16^a therein. The guard or cover 12 is cut away at its lower edge so as to span the lugs 15, as best shown in Fig. 1. Screws 60 or other fastening means 17 connect the cover 12 with the ring 5.

A shallow cup-like member 18 is disposed on the back of the reproducer, and includes a plate 19 having an annular upstanding 70 flange 20. A soft rubber gasket 21, of considerable thickness, is disposed partly within the member 18, and screws 22 hold the gasket in place. The gasket is provided with inner and outer annular beads 23 and 24, which project beyond each of its surfaces, as best shown in Fig. 2.

75 Bushings 25 surround the screws 22 and extend through the gasket and contact with the plate 19 of the member 18 when the screws 80 are driven home. When so driven, the heads of the screws are in contact with the exposed ends of the bushings although such heads project beyond the bushings and contact with the gasket. The inward movement 85 of the screws is limited by the bushings. The heads of the screws are countersunk. As shown, the screws are threaded into the back of the sound-box, and into the member 18, and with the bushings serve to hold the 90 member 18 to the back of the sound-box. However, if it is desired, this member 18 may also be sweated or otherwise secured to the back.

95 Disposed on the opposite side of the gasket 21 is a coupling member 26, including a connecting portion or nipple 27 and a flat portion 28 having an annular flange 29 forming a shallow cup-like member adapted to embrace a portion of the outer periphery of the gasket. This coupling member is secured to the gasket by means of screws 30 and bushings 100

31, similar in structure and function or operation to the screws and bushings 22 and 25 respectively, used for connecting the gasket with the member 18. The heads of screws 5 30 are countersunk in the gasket but beyond the bushings engage a portion of the gasket to secure it to the coupling.

In the actual assembling of the device, the gasket 21 is first secured to the coupling member 26 by means of the screws 30 and bushings 31. Then, as a unit, this structure is secured to the member 18 and the entire assembly is attached to the back of the sound-box. Otherwise, the member 18 may first be 10 secured to the back of the sound-box and the gasket 21 and coupling 26, as a unit, secured to it. Openings 32 are formed in the part 15 28 of member 26 to admit of the insertion of a screw driver for securing screws 22 in the 20 assembling operation.

In view of the fact that the gasket is formed of soft rubber, the bushings have a special significance, in that they prevent the threading of the screws into and through the back 25 of the sound-box in such a way as to pull their heads through the gasket. Without the bushings, this would be possible in view of the 30 softness of the gasket.

The annular ribs or beads, 23 and 24, 30 formed on the gasket, effectively seal the space between the coupling 26 and the member 18 and prevent any leakage of sound. This is due to the fact that should there be any compressing of the rubber the force will be 35 taken up in the ribs or beads. Moreover, these ribs or beads maintain the major portion of the gasket spaced from the members 18 and 26 and in this way prevent the heads of screws 22 and 30 from coming into contact 40 with the parts 19 and 28 respectively, during the vibration of the device, and in this manner setting up a rattling or other metallic sound.

Flanges, 20 and 29 of members 18 and 26 45 serve to distribute and render harmless any lateral pull on the members. Otherwise, such pull or force would of necessity be taken care of by the heads of the screws 22 and 30 and in a short time the holes in the gasket would 50 be so enlarged that the heads of the screws would pass through them. In this function, the annular flanges are materially aided by the bushings which surround the screws.

The sound-box carries stops designed to 55 limit movement of the stylus or needle arm. Excessive movement of this arm is apt to result in the fracture or breakage of the diaphragm. These stops comprise a pair of pins 33 and 34 disposed above and below the pivot 60 point of the stylus arm and secured in ears 35 which are carried by the plate 36 that supports the mounting means for the stylus arm. This plate may be sweated or otherwise secured to the ring 5. The pins 33 and 34 are 65 adjusted to within a few thousandths of an

inch of the stylus arm and are locked in that position by small nuts 37 which may be waxed to secure them against casual movement.

What is claimed is:

1. Means for connecting a sound-box to a tone-arm, the same comprising a pair of shallow cup-like members, a connecting nipple carried by one of said members, a soft rubber gasket disposed between said members and extending partly into each of them and filling 75 the space between them, screws connecting said gasket to one of said members, other screws connecting said gasket to the other of said members, bushings disposed about said screws and in contact with said respective 80 members and with the heads of the screws to limit the pressure that may be exerted on the gasket by the screws.

2. Means for connecting a sound-box to a tone-arm, the same comprising a pair of shallow cup-like members, a connecting nipple carried by one of said members, a gasket disposed between said members and extending partly into each of them and filling the space 85 between them, screws connecting said gasket to one of said members, other screws connecting said gasket to the other of said members, and said last-mentioned screws also operable to secure the other of said members to the back 90 of a sound-box.

3. Means for connecting a sound-box to a tone-arm, the same comprising a pair of members each including a plate having an annular flange, a connecting nipple carried by one of said members and projecting in a direction 100 opposite to the flange of said member, said members being arranged with their flanges directed toward each other, a soft rubber gasket disposed between said members and extending into each of them in snug engagement 105 with said annular flanges, means securing the gasket to said members and said gasket holding said members in spaced relation.

4. Means for connecting a sound-box to a tone-arm, the same comprising a member including a plate having an annular upstanding flange, a gasket of resilient material, said member adapted to partially receive said gasket with its flange snugly engaging the 110 same, a second member including a plate having an annular flange directed towards the flange of said first-mentioned member, said second member adapted to receive a portion of the remainder of said gasket and have its 115 flange snugly engage the same, a connecting nipple carried by said second-mentioned member, fastening means to connect the gasket to the first-mentioned member, said fastening means also operable to secure said member to the back of a sound-box, other fastening means connecting said gasket to the second-mentioned member, and bushings disposed about said fastening means and in contact with said respective members and fasten- 120 125 130

ing means to limit the pressure exerted on the gasket by the fastening means.

5. Means for connecting a sound-box to a tone-arm, the same comprising a pair of shallow cup-like members each including an annular flange, a connecting nipple carried by one of said members and projecting in a direction opposite to the flange of said member, a soft rubber gasket arranged between said members and extending into each of them in snug engagement with their annular flanges, and means securing the gasket to said members, said gasket holding said members in spaced relation.

15 6. Means for connecting a sound-box to a

tone-arm, the same comprising a pair of shallow cup-like members each including an annular flange, a connecting nipple carried by one of said members and projecting in a direction opposite to the flange of said member, 20 a rubber gasket disposed between and extending partly into each of said members in snug engagement with their annular flanges, means securing said gasket to one of said members, and separate means securing the gasket to the 25 other of said members.

Signed at Bridgeport, in the county of Fairfield, and State of Connecticut, this 7th day of June, A. D. 1926.

FRANK C. HINCKLEY.
